UNITED STATES PATENT OFFICE.

SIGISMONDO DIAMANT, OF GENOA, ITALY, ASSIGNOR OF ONE-HALF TO CARLO SCOTTI,
OF GENOA, ITALY.

VALVE-CONTROLLING DEVICE FOR ENGINES AND MOTORS.

Application filed November 5, 1924, Serial No. 747,958, and in Italy May 9, 1924.

The present invention relates to a controlling device manually or automatically operated for the valves of internal combustion engines of any kind.

5 In internal combustion engines provided with puppet valves, each cylinder is provided with an inlet and an exhaust valve, which open generally by moving vertically. These valves are suitably connected to a 10 downwardly extending stem on which acts a cam keyed on a secondary shaft called a cam shaft, driven from the main motor shaft and revolving with half the angular speed of this latter. The angle at which the cams 15 are keyed and their shape are suitably chosen according to the operating conditions. As these characteristics in the types of engines now in use are fixed for each type, the actuation remains for any and each type of engine the same, at all speeds.

The object of the present invention is to provide improved means adapted to vary the timing of the actuation either for each speed of running or for reversing the movement.

25 With the above and other objects in view the invention consists in the construction, combination and arrangement of devices hereinafter described and claimed.

The drawings represent the device in its 30 different positions and as applied to two valve controls of a four-stroke explosion motor. In these drawings:

Figure 1 is an end elevation of the whole of the device to control the inlet valve.

35 Figure 2 is a plan view of Figure 1.

Figure 3 is a side view of the group of two distributing levers for the inlet valve.

40 Figure 4 is an end view of the whole of the two groups comprising the four distributing levers for the two valves of a cylinder, each group being constituted by two arms that operated the same valve, one of which serves for the ahead rotation and the other for the reverse rotation.

45 Figure 5 is an end elevation partly in section of the controlling device for the inlet valve with the cam arranged for maximum angular speed.

50 Figure 6 is a similar view showing the controlling device for the outlet valve with

the cam arranged for maximum angular speed.

Figure 7 is a similar view showing the controlling device for the inlet valve with the cam arranged for angular minimum 55 speed.

Figure 8 is a similar view showing the controlling device for the outlet valve with the cam arranged for angular minimum 60 speed.

Figure 9 is a similar view showing the controlling device for the inlet valve but with the cam arranged for reversed rotation at maximum speed.

Figure 10 is a similar view showing the 65 controlling device for outlet valve but with the cam arranged for reversed rotation at maximum speed.

Figures 11, 12 and 13 are respectively vertical, transverse and horizontal sections, with 70 portions in view, showing the complete assembly relating to a cylinder of the motor with slight constructional variations in respect to the device shown in the previous 75 figures.

Referring to the drawings and particularly to Figures 1, 2, 3, 4, 11, 12 and 13, M denotes the distribution or secondary shaft, that is controlled by the main motor shaft; Na and Ns indicate the outer ends of the distribution levers controlling respectively the inlet and exhaust valves of each cylinder of the motor. These levers are usually formed as radial arms R, keyed on the shaft M at the proper angular positions and fitted at 80 their ends with suitable rollers Na and Ns. According to this invention in order to provide means adapted to vary the distribution, the secondary shaft M does not act directly through a suitable cam on each valve stem 85 V, but acts through means of an intermediary member consisting of a lever C, fulcrumed on a regulating shaft E parallel to M. This lever C bears with one of its ends, C'', against the valve stem V and is controlled by the shaft M by action of the said radial distribution arm R, which acts by means of the correspondent contact roller 90 against the shaped surface of a slide fastened to the lever C, thus imparting to said 95

100

- slide and attached lever C, C'', rocking movement. This slide is constituted in two parts, indicated by the references A and B in the inlet valve controlling as shown in Figure 1, these two parts being pivoted in the manner of scissor blades at D, which pivot D is fixed to the lever C; and each of the said parts A, B extend from the opposite side with a projecting member A', B'. 10 These projections form the hilt of the scissors.

In the drawings the parts of the slide controlling the exhaust valve are indicated by the references H and I, and their projecting members respectively by H' and I'.

A spring G tends to widen the aperture of the slide and is opposed by a fixed cam F keyed on the shaft E and on which bear the outer ends of the projecting member A', B', or H', I'.

The lever C, by its own weight and the thrust of the valve stem V, bears the lower surface of its slide into the path of the corresponding arm R which, by rotating, meets this surface with its roller, causing the rocking of the lever C and the lifting with its flat end C'' the valve stem V. The opposite end C' of the lever C is socketed to receive the end of a compressing spring S making contact with a suitable nut T supported in the casing L of the engine. While the shaft E is constantly maintained in a determined position, the cam F also remains in the same position and therefore the aperture of the mouth of the slide does not appreciably vary, and thus the roller of the corresponding arm R on shaft M always meets the same shape of slide, and consequently the valve stem is always lifted to the same extent and 30 during the same angle of revolution, resulting in a constant distribution; but it will suffice to turn the controlling shaft E at a certain angle in order to vary the distance of the points of the projecting member, for instance A', B', leaning on cam F, thus changing the aperture of the scissors and the shape of the slide, and modifying the distribution.

Now it is easily understood that by giving, as is hereinafter more particularly described, suitable shapes to cams F for the inlet and to the cams F' for the exhaust, the distribution could be varied to any desired extent and in accordance with the speed of running of the motor.

In order to reverse the movement of the motor, other rotating arms R are provided mounted on the shaft M, the operating ends of which arms, respectively N'a and N's, will meet the slide surfaces of the corresponding lever C, while the shaft M turns in reverse direction. For obtaining the proper distribution also in the reversed rotation of the motor, these arms ending in N'a and N's are, as shown in Figure 4, diametrically opposed

respectively to the arms ending in Ns and Na controlling the same inlet and exhaust valves when the engine is running ahead. The cams F and F' have a portion of their contour suitably shaped for obtaining the apertures of the scissors, and the shapes of the slide, convenient to the reverse motion.

The rotating arms ending in N'a and N's are keyed on the shaft M at the same side of the corresponding arms Na and Ns, and so disposed that it is possible to place all of the arms for the reversed rotation under the slides of the corresponding lever C by causing the shaft M to slide axially for the space corresponding to the equal distance between each arm for the ahead rotation and the relative arm for the reverse rotation. Contemporaneously the shaft E must be rotated to the angular position, in which the cams F and F' give to the scissors the suitable aperture and consequently to the slides the shapes adapted for the reverse rotation, thus enabling the engine to run in reverse direction at the desired speed.

As will be seen from the drawings, the device according to the present invention may assume, correspondingly to the position of slipper, different shapes of contact surfaces for controlling the inlet and exhaust valves. Each of these devices is formed by two levers oscillating around a fixed point, one of said levers projecting beyond both sides of the said fixed point while the other lever ends at said fixed point. The projecting portion of the first lever and the portion of the second lever nearest the pivot are flattened and so-shaped as to form together a curved surface having its concavity directed downwardly, said surface constituting a slipper or slide, the highest point of which is placed substantially on the vertical line beneath the pivot so as to correspond to the end of the two half-slides or slippers. The internal surfaces of the slides are of the form of a cylinder whose axis corresponds with the axis of the bearing pivot.

By such arrangement, whether the said levers are approaching or receding, the curve formed by the two parts of the slide can be modified, though remaining always a continuous one. Each of these curves can be approximately compared to an arc of circle whose radius is larger than the radius of the circle described by the peripheral point of the rotating arm, which contacts with the surface of the slide. Because of the said difference of the radii, the roller will raise the surface of the slide and consequently the valve to a height corresponding to the difference of the heights of the arc of the crutch and of that described by the peripheral point of the roller of the arm, between the first and the last point of contact with each other, and consequently having both the chords equal to the distance of these two points.

It follows that the point of the arc which comes first into contact with each roller represents the opening moment, and the point which is abandoned by the roller, the closing moment of the valve which takes place after the roller has passed over all of the guide surfaces between the said points. The chord of the arc of contact thus indicates the period during which the valve is open.

10 It is obvious that in order to modify the form of the contact surface which constitutes the slide, it is sufficient to cause the two levers of the system to be brought closer together or to move them farther apart, and 15 in fact, by bringing the levers nearer together the chord of the arc is prolonged, and thus the opening period is increased, while if they are moved apart, the chord is shortened and thus the opening period is 20 decreased.

The adjustment of the levers to bring them together or move them farther apart can be effected either by moving one of the said 25 levers, or by moving both levers, the one independently of the other, whereby, in addition to the increasing or diminishing of the opening period there is obtained an advance or a delay of the closing period to a degree that is found suitable.

30 In order to effect this, the two levers are so arranged with bayonet joint fittings that they are alongside each other and are yet so placed that their ends come in the same vertical place so that between one and the 35 other lever there can be arranged a cam against which the said two levers are forced by means of a suitable compressing spring with contact points diagonally opposite. Said cam is keyed on the regulating shaft 40 and suitably shaped on the one and on the other of its peripheral halves in such manner as to produce, by its rotation, the moving apart or the bringing together of the said two lever ends, the one independently 45 of the other and consequently varying the form of the corresponding slide or slipper surface.

It is to be understood that the levers instead of being fitted with bayonet-like joints 50 could be disposed in any other suitable form provided the two cam shapes which are then used respectively to actuate said surfaces are so placed as to equally cause the working of said surfaces. If, for instance, said 55 levers should be right they could be driven the one independently of the other by means of a proper cam and in this case the shape of each cam should be developed along all of the cam periphery instead of one half 60 only of said periphery.

Referring to Figures 5, 6, 7, 8, 9 and 10, the working or operation of the apparatus is as follows:

The regulating shaft E together with the 65 cams F and F' are placed as shown in Fig-

ures 5 and 6 in a position for the ahead working of the motor at maximum angular speed.

In Figure 6 the lever H' of the device for the exhaust valve is raised and maintained 70 by the cam F' at the position 2'; consequently, its opposite end H, which constitutes the external half of the slipper is lowered to the position 2.

The lever T' in its turn is maintained by 75 the same cam at the position 2'', and with it also the internal half I of the slide, which is in one piece with the lever, and is placed at the position 2'''. The form of the bearing slipper I-H is such that the distributing roller, by turning, comes into contact with it at the position N', thus beginning 80 the valve opening. In the drawing the said position is shown as placed at 25° in front of the dead center which is indicated by 85 the line O and it corresponds with 50° of the motor crank shaft before the end of the expansion period.

When the roller has arrived at the position n', (the end of the period) which is 90 shown on the drawing as at 5° past the dead center O' (10° of the crank), the roller itself leaves the slide or slipper and the valve is closed. The maximum rise of the valve 95 is reached at the position N'.

As soon as the exhaust period is finished, the inlet period then begins. The cam F, Figure 5, maintains the lever A' raised at the position 2', and consequently its opposite end A which constitutes the external half of 100 the slide is lowered to the position 2. The lever B' is placed on the position 2'' so that the internal half B of the slide being in one piece with it, will be placed at the position 2'''. Owing to such an arrangement the 105 distributing roller will engage with the slipper beginning to open the valve at the position N' at 5° (crank 10°) past the dead center O and will leave the slipper closing the valve at the position n'-20° (crank 40°) 110 past the dead center O' when the piston has already begun the compression period.

These opening and closing moments of the valve are those usually adopted by the builders of motors that have a speed of 115 about 1500 revolutions per minute. If such motors should reduce their angular speed also maintaining unchanged the aforesaid moments, the turning moment would rapidly decrease and in such a way that at 300 120 or 400 revolutions per minute said moment should be almost zero.

In order to avoid such a great disadvantage and obtain at any angular speed a maximum turning moment proportioned to the 125 useful volume of the cylinder as well as to the piston area, by utilizing the device according to the present invention, the regulating shaft E will be gradually turned in the direction of the arrow and in relation to 130

the fixed angular speed. The cams suitably shaped will then successively so dispose the slides or slippers as to effect the valve opening and closing at the most appropriate moments.

Figures 7 and 8 show the position of the cams for a minimum angular speed. The levers are resting on the cams in positions corresponding to the points 3', 3'' and the 10 slides take up the positions 3, 3'''. In this case the exhaust valve Figure 8 will open at 7° (crank 14°) before the end of the exhaust phase and will close at 3° (crank 6°) after the dead center O'. The inlet valve 15 Figure 7 will open at 3° (crank 6°) at the beginning of the period and will close at 7° (crank 14°) at the end.

By turning the regulating shaft E further in the direction of the arrow and changing 20 the lever contact position from the positions 3', 3'' to 4', 4'' and the slides to the positions 4, 4''' there will be gradually obtained the changed conformation of the slippers for the reversed rotation of the motor. Figures 25 9 and 10 show precisely the positions of the cams as well as of the slippers arranged for the maximum angular speed in the reverse direction.

By turning the motor in the reversed 30 direction also the cam shaft will turn in the same direction. The rollers N'a and N's which are now brought into action by sliding the shaft M axially, will make contact and will open the valves at the positions N³ 35 and will leave the slippers for closing the valves at the position n³. Also in this case and in connection with the whole range of the angular speed from maximum to minimum the valves will open and close during the ahead direction.

In Figures 5 and 6 there is represented by dotted lines, also the positions of the slippers and of the corresponding rollers similar to Figures 7 and 8 and to Figures 9 and 45 10 respectively.

The opening and closing periods of the valve heretofore described are only given naturally by way of example. Any period 50 may be chosen according to judgment and experience.

Figure 1 shows another example of opening and closing periods for the inlet valve.

The movement of rotation of the regulating shaft E bearing the cams, may be limited to $\frac{1}{2}$ of a revolution only (about 55 150°), and it may be obtained as will be understood either by means of hand operation, or by means of any other already known device.

Although for descriptive reasons the present invention has been described with relation to the constructions set forth, nevertheless many other modifications could be introduced especially with regard to the forms 60 and dimensions of the various members con-

stituting the valve controlling device, and this without departing from the fundamental principles of the present invention as claimed in the following claims.

Having now particularly described and ascertained the nature of my said invention and in what manner the same is to be performed, I declare that what I claim is:

1. Internal combustion engine valve controlling mechanism comprising a valve operating lever, a regulating shaft on which said lever is pivotally mounted, a cam fast to said shaft, a pair of crossed controlled levers pivotally connected together at their point of intersection, said controlling levers bearing at one end on said cam at points on opposite sides of said regulating shaft and being provided at their opposite ends with slides, a distribution shaft, and means on said distribution shaft to consecutively contact with said slides and thereby actuate said controlling levers and hence said valve operating lever.

2. Internal combustion engine valve controlling mechanism comprising an inlet valve operating lever and an exhaust valve operating lever, a regulating shaft on which said levers are pivotally mounted, cams fast to said shaft, a pair of crossed controlling levers associated with each valve operating lever, each pair of said controlling levers being pivotally connected together at their point of intersection and said pairs of controlling levers having a common pivot at their points of intersection, each pair of said controlling levers bearing at one end on one of said cams at points on opposite sides of said regulating shaft and being provided at their opposite ends with slides, a distribution shaft, and means on said distribution shaft to consecutively contact with the slides of one pair of said controlling levers and thereby actuate said controlling levers and hence also said valve operating levers.

3. Internal combustion engine valve controlling mechanism comprising a valve operating lever, a regulating shaft on which said lever is pivotally mounted, a cam fast to said shaft, a pair of crossed controlled levers pivotally connected together at their point of intersection, a spring causing said controlling levers to bear at one end on said cam at points on opposite sides of said regulating shaft, said controlling levers being provided at their opposite ends with slides, a distribution shaft, and means on said shaft to consecutively contact with said slides and thereby actuate said controlling levers and hence also said valve operating lever.

4. In a device for controlling the opening of the distributing valves of internal combustion engines to vary the amplitude and the position in the cycle of the distribution phases and hence allow the engine to de-

- velop maximum power; the system for controlling the said valves comprising a plurality of levers arms, a distribution shaft on which said lever arms are mounted and arranged to turn with the main motor shaft, and a plurality of shaped surfaces through which the opening of the valves is regulated and on which act the aforesaid lever arms; the shaped surfaces being formed by a succession of consecutive members that are adjustable relatively to each other in such a manner as to vary suitably the position of the said active surfaces and thereby vary the shape of the contact surface as a whole, according to the speed and turning direction of the motor, in order to obtain a constant volume efficiency at all angular speeds or in either direction of rotation.
5. In a device for controlling the opening of the distributing valves of engines of any kind in order to vary the amplitude and the position in the cycle of the distribution phases, by letting in at the most suitable time always a determined amount of fuel mixture at any angular speed so that the cylinders may never work incompletely filled, thus allowing the engine to develop always its maximum power; a system for controlling the said valves constituted by a lever arm device mounted upon the distribution shaft and turning with it in connection with the main motor shaft, the active part of the said arm acting upon a plurality of shaped surfaces formed by a succession of consecutive members that actuate the valves and are adjustable relatively to each other in order to change conveniently position of the said contact surfaces and thereby vary the shape of the contact surface as a whole according to the angular speed of the main motor shaft; the said consecutive members that bear the portions of the active shaped surfaces being supported by a lever which actuates by one of its ends the stem of the valve.
6. In a device for controlling the opening of the distributing valves of engines of any kind in order to vary the amplitude and the position in the cycle of the distribution phase, allowing the engine to develop always its maximum power by obtaining a constant volume efficiency at all angular speeds and in either direction of rotation; a system for controlling the said valves constituted by plurality lever arms mounted upon the distribution shaft *a* and turning with it in connection with the main motor shaft; a plurality of shaped surfaces through which the time of opening of the valves is controlled and upon which the aforesaid rotating arms, operate shaped surfaces formed by a succession of consecutive members constituted in the form of scissor-blades mounted upon a journal that is supported by the same lever that actuates the valve stem and the scissor-blade members being adjustable relatively to each other in such manner as to change conveniently the position of the said contact surfaces and thereby vary the shape of the contact surface as a whole according to the speed and the turning direction of the motor.
7. In a device for controlling the opening of the distributing valves of internal combustion engines of any kind in order to vary the amplitude and the position in the cycle of the distribution phases, allowing the engine to develop always its maximum power by obtaining a constant volume efficiency at all angular speeds or in either direction of rotation, a system for controlling the said valves which is constituted by a lever arm device mounted upon the distribution shaft and turning with it in connection with the main motor shaft; a plurality of shaped contact surfaces formed by a succession of consecutive members constituted in the form of scissor-blades in such a way that the portions of the shaped contact surfaces might have any required position for letting in a determined amount of fuel mixture at the different angular speeds and turning direction of the motor.
8. In a device for controlling the opening of the distributing valves of internal combustion engines of any kind in order to vary the amplitude and the position in the cycle of the distribution phases to permit the engine to develop always its maximum power by obtaining a constant volume efficiency at all angular speeds or in either direction of rotation; the arrangement upon the distribution shaft of a plurality of lever arms acting upon a plurality of shaped contact surfaces that are formed by a succession of consecutive members constituted in the form of scissor-blades, having the variable surfaces which contact with the ends of the said lever arms are mounted on the same turning shaft, each of the scissor-blade members having a projecting arm, the said arm being operatively connected with a supporting and valve-actuating lever, the ends of the said arms being drawn nearer together or moved farther apart in accordance with the amount of work and the direction of rotation of the motor by means of cams of any known kind, mounted on a regulating shaft upon which is loosely mounted the supporting lever, in order to change the position of the said contact surfaces according to the speed and the turning direction of the motor.
9. In a device for controlling the opening of the distributing valves of internal combustion engines of any kind in order to vary the amplitude and the position in the cycle of the distributing phases so as to permit the engine to develop its maximum power by obtaining a constant volume effi-

ciency at all angular speeds and in either direction of rotation, the said controlling being effected by means of lever arms acting upon a plurality of shaped contact surfaces, 5 the form of which can be varied according to the angular speed of the motor shaft; the arrangement of the said lever arms that act upon the shaped surfaces mounted parallel to the distribution shaft and upon a journal 10 which can be displaced axially in order that the said lever arms may actuate either the shaped surfaces for the ahead rotation or those for the reverse.

10. In a device for controlling the opening 15 of the distributing valves of engines of any kind in order to vary the amplitude and the position in the cycle of the distribution phases to permit to the engine to develop its

maximum power at all angular speeds and in either direction of rotation, the said controlling being effected by means of a plurality of lever arms acting upon a plurality of shaped contact surfaces, the form of which can be changed in connection with the angular speed of the motor shaft; the 25 special arrangement of two consecutive portions of the active shaped surface in such a manner that they may be simultaneously controlled by means of a governor through which the shape of the total surface upon 30 which the said rotating arms act is varied, in order to let into the cylinders the required amount of fuel mixture.

In witness whereof I affix my signature.

SIGISMONDO DIAMANT.
